United States Patent Office

Des. 183,149
Patented July 1, 1958

183,149

TRACTOR SEAT OR THE LIKE

Allison K. Simons, Whitefish Bay, Arthur O. Radke, Wauwatosa, and Joseph A. Champa, Milwaukee, Wis., assignors to Hickman Industries, Inc., Eden, N. Y., a corporation of New York

Application December 6, 1956, Serial No. 44,078

Term of patent 14 years

(Cl. D14—6)

Fig. 1.

Fig. 2.

Fig. 3.

Fig. 4.

Fig. 1 is a top plan view of the tractor seat or the like embodying our new design.

Fig. 2 is a side elevational view thereof, the opposite side elevational view being substantially the same.

Fig. 3 is a front elevational view thereof.

Fig. 4 is a rear elevational view thereof.

We claim:

The ornamental design for a tractor seat or the like, substantially as shown.
